US00D648334S

(12) **United States Design Patent**
Andre et al.

(10) **Patent No.:** US D648,334 S
(45) **Date of Patent:** ** Nov. 8, 2011

(54) **PORTABLE COMPUTER**

(75) Inventors: **Bartley K. Andre**, Menlo Park, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Douglas B. Satzger**, Menlo Park, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/396,081**

(22) Filed: **Jun. 24, 2011**

Related U.S. Application Data

(60) Continuation of application No. 29/384,006, filed on Jan. 25, 2011, which is a continuation of application No. 29/366,369, filed on Jul. 23, 2010, now Pat. No. Des. 633,087, which is a continuation of application No. 29/351,847, filed on Dec. 11, 2009, now Pat. No. Des. 623,645, which is a continuation of application No. 29/337,518, filed on May 22, 2009, now Pat. No. Des. 606,988, which is a division of application No. 29/326,309, filed on Oct. 15, 2008, now Pat. No. Des. 604,292, which is a continuation of application No. 29/326,082, filed on Oct. 10, 2008, now Pat. No. Des. 604,290.

(57) **CLAIM**

The ornamental design for a portable computer, as shown and described.

DESCRIPTION

FIG. 1 is a front, top perspective view of a portable computer showing our new design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines are for the purpose of illustrating portions of the portable computer and form no part of the claimed design. The black shading on the front of the screen represents the color black and the dark gray shading on the front of the screen represents the color gray.

1 Claim, 6 Drawing Sheets
